UNITED STATES PATENT OFFICE.

HARRY I. CRAMER, OF DAYTON, OHIO, ASSIGNOR TO THE STERLING JEWELRY COMPANY, OF DAYTON, OHIO, A CORPORATION OF OHIO.

DESIGN FOR A WRIST WATCH.

Application filed February 20, 1928. Serial No. 25,494. Term of patent 7 years.

To all whom it may concern:

Be it known that I, HARRY I. CRAMER, a citizen of the United States, residing at Dayton, in the county of Montgomery and State of Ohio, have invented a new, original, and ornamental Design for a Wrist Watch, of which the following is a specification, reference being had to the accompanying drawing, forming a part thereof.

In the accompanying drawings:

Fig. 1 is a face view of a wrist watch showing my new design; and

Fig. 2 is a view of the stem end of the watch.

I claim:

The ornamental design for a wrist watch, as shown.

HARRY I. CRAMER.
